UNITED STATES PATENT OFFICE.

HIPPOLYTE M. CHIRON, OF HOG ISLAND, PENNSYLVANIA.

AEROPLANE.

1,305,524.

Specification of Letters Patent. Patented June 3, 1919.

Application filed August 3, 1918. Serial No. 248,130.

To all whom it may concern:

Be it known that I, HIPPOLYTE M. CHIRON, a citizen of France, and resident of Hog Island, Pennsylvania, have invented certain 5 new and useful Improvements in Aeroplanes, of which the following is a specification.

My invention includes front and rear frame members adapted to be separated from each other, the front member carrying 10 the engine and heavier parts of the aeroplane and the rear frame carrying the rudder, together with a parachute connected with the aviator, so that in case of accident or at the will of the operator the front and 15 rear frames may be separated from each other and will cause the dislodgment of the aviator from both frames, so that he will descend by means of the parachute independently of the two frame parts of the 20 machine.

I also provide means whereby the rear part of the machine will be retarded in its descent so as not to interfere with the descent of the aviator by means of the parachute.

25 Other features of my invention will appear from the following description and from the appended claims.

In the drawings,

Figure 1 is a side view of an aeroplane 30 embodying my invention.

Fig. 2 is a plan view.

Fig. 3 is a front view.

Fig. 4 is a side view of the aeroplane with its inclosing casing.

35 Fig. 5 is a view of the front portion or frame of the machine in the act of dropping away from the aviator and the rear portion.

Fig. 6 shows the rear portion of the 40 machine in the act of descending when separated from the front portion.

Fig. 6^a is a view of the aviator descending from between the front portion of Fig. 5 and the rear portion of Fig. 6.

45 Fig. 7 is a detail view partly in section of the means for controlling the separation of the two frame parts of the apparatus.

Fig. 8 is a detail view of a weight and the parts associated therewith, which will operate when the weight is dislodged.

Fig. 9 is a detail view of certain gear connections.

Fig. 10 is a plan view partly in section, of bolt locking means of certain parts of the 55 front and rear frames.

Fig. 11 is a detail view showing pivoted rear wing portions and means for holding the same in position.

Fig. 12 is a detail view of part of Fig. 7.

Fig. 13 is a detail view of another part of 60 Fig. 7.

Fig. 14 is a plan view of the bolt or locking means of Fig. 10.

Fig. 15 is a detail view of one of the blocks or lugs of Fig. 12.

Fig. 16 is a detail view of one of the blocks or lugs of Fig. 13.

Fig. 17 is a detail of another block.

Fig. 18 is a detail view of the front and rear frame connection.

In these drawings 1 indicates the front 75 frame of the apparatus which may be of any desired type and 2 the wheels mounted thereon. 3 is a weight in a receptacle 4 carried by an arm or frame 5 pivotally mounted to the

main front frame at 9, and having an arm 7 connected with a pin and slot joint at 8 with the rod 10. The weight can be dislodged by the plane assuming an abnormal position and when this takes place the front 80 and rear frame portions of the apparatus will be separated, as hereinafter described and the aviator with his parachute will be dislodged and dropped from between these frames.

The dislodgment of the weight 85 will allow a spring 11, Figs. 1 and 8, to force the rod 10 downwardly out of engagement with the end 12, Fig. 7, of a slide 13, which will then be pressed to the right in its guide

casing 14 carrying the rod 16 with it, which 90 will draw upon two chains 17 and 18, which pass over the pulleys 19 and 20, and thus the bolts 21 will be drawn to the left, Figs. 1, 7, 10, so that the spring arms 33 will be released to fly out from the position

95 shown in Fig. 1 to that indicated in Fig. 6, and as a result the front frame with the engine propeller, wheels, and other parts will be separated from the rear frame part 33' for the release of the aviator with his 100 parachute, as will be more particularly described hereinafter.

The bolt 21 has portions 21^a and 21^b which engage through lugs 23 on the front frame and through lugs 32 on the spring 105 arms 33. The bolt arrangement 21 has side arms or rods 22 connecting the front and rear portions thereof and this bolt arrangement is pressed toward the right into engaging position by the spring 31. The 110

blocks or lugs 32 have openings 26 to receive the bolt, Fig. 15, and the blocks 23 have openings 26', Fig. 16, for receiving the bolt and openings 25 are arranged in the block 5 to receive the side bars 22 of the bolt arrangement. At 27 on the front frame there is a guide lug for receiving a portion of the bolt arrangement to guide the same. The front and rear frames are connected together by eyes or lugs 34 carried by the bar 35 of the front frame portion, these lugs receiving between them the front ends 36 of the rear frame bars 33', pins 38 passing through the lugs 34 and ends 36, said pins 10 being connected or carried by the flexible or spring arms 33, so that when these arms fly outwardly the bolts 38 will be withdrawn to disconnect the front frame from the rear frame. 15 39 is a horizontal lever centrally pivoted on the front frame adapted to be operated by the feet of the aviator and having ropes 40, 41 connecting this lever with a lever 43, which is connected with a gear 42 mounted 20 on the front frame portion of the machine. 25 Gear 42 meshes with a gear 44 mounted on the rear portion of the machine and to the latter gear a horizontal lever 45 is connected from which ropes 46, 47 extend to 30 the rudder 48, so that the operator can control the same, when the parts of the machine are all connected together, but when the front frame part is separated from the rear frame part the gearing will separate from 35 each other and will not in any way obstruct the complete separation of the front and rear frames of the machine. 49, Fig. 9, is a gear carried on the front part or frame of the machine and engaging with gear 50 mounted 40 on the after frame of the machine. With the gear 50 a horizontal lever 51 is connected, from which ropes 52, 53 lead over a pulley 54 mounted on the pivot or shaft of the rear wings 55, so that the operator may operate 45 these wings. 56 indicates a steering wheel on the front part of the machine. 57 indicates a lever pivotally mounted at 57^a on the front frame section adapted to be operated by the aviator, this lever being connected with the rod 10, which, when operated, will, as above described, through the connections mentioned cause the separation of the front frame portion, so that the aviator when he considers himself in danger can 50 55 separate the fore and aft parts of the machine and with his parachute drop down between these separated portions. 58 indicates ropes extending from the spring arms 33 around pulleys 59 on the rear frame part 60 and connecting at the rear with bolts 60 passing through ears 62 on the rear frame section and through ears 63 connected with the wings 61 at the rear of the after frame of the machine, these wings being adapted 65 to turn from a position in the same plane with the longitudinal axis of the machine to a position at right-angles thereto. 64 indicates ropes extending from the flexible or spring arms 33 over the pulleys 65 and 66, the said ropes being attached to the arms 67 70 attached to and extending perpendicularly to the plane of the rear wings 61. The rear wings are adapted to turn about the axis 68 and they will turn when the flexible arms 33 fly outwardly, because these arms in moving out will draw upon the ropes 58 and 64, the ropes 58 releasing the bolts at 60 and the ropes 64 drawing upon the arms 67 and turning the wings from their normal position to a position at right-angles thereto, 75 that is from the position of Fig. 2 to the position of Fig. 6, so that these wings in the latter position will retard the fall of the rear portion of the frame shown in Fig. 6, allowing the front heavy portion, shown in 80 Fig. 5, to fall rapidly and allowing also the fall of the aviator to take place without danger of being struck by the rear frame member. 69 indicates springs for normally holding the bolts 60 in place to lock the rear 85 wings against turning. 90 95 100 105 110 115 120 125 130 135

70 indicates a stiffener bar bearing upon the inner sides of the flexible arms 33, over which said arms are tensioned or stressed. 71 is the aviator's seat, which is pivoted at 72 and held in normal position by resting on the lug 73 of the front frame, so that when the front frame is separated from the rear frame the weight of the aviator will throw the seat downwardly and he will slide off therefrom. The parachute which is attached to the aviator is indicated at 74, and 75 is the propeller. 76 and 77 are the front wings. 78 is a rope connecting the weight 3 to the front of the machine.

Briefly stated the operation is that when the machine assumes a position of danger the weight will be dislodged allowing the spring 11 to exert its force and as a result the rod 10 will be operated to release the bolt mechanism by the chains 17, 18, thus allowing the spring arms 33 to fly outwardly and disconnect the front frame portion from the rear frame portion and also setting the wings 61 in position to retard the descent of the rear frame portion.

The operator, when the frame portions are separated, slides from the seat and then descends between these frames, as illustrated in Figs. 5, 6, and 6^a considered conjointly. The aviator can of course effect the same operation that is secured by the weight 3 by simply operating the lever 57.

What I claim is:

1. In combination in an aeroplane, a front frame section, a rear frame section, a seat for the aviator substantially at the junction of the two frames, means whereby the two frames are detachably connected together and a parachute arranged to drop

- free from both frames with the aviator when said frames are separated, substantially as described.
2. In combination in an aeroplane, a front frame section carrying the engine, propeller and supporting wheels, a rear frame section detachably connected with the front frame section and carrying the rudder, means on the rear frame section, shiftable from normal position into a position to retard the descent of the rear frame section in respect to the front frame section, when said sections are separated, a parachute arranged to drop free in respect to both sections when said sections are operated, whereby the aviator may descend independently of the front and rear frame sections, substantially as described.
3. In combination in an aeroplane, a front frame section, a rear frame section, detachable connections between said sections, whereby said sections will separate from each other to descend independently, a seat for the aviator arranged adjacent the junction of the two sections, and means for supporting the seat in normal position when the frame sections are connected, but to move from said normal position to facilitate the dislodgment of the aviator when the front and rear sections of the frame are separated and a parachute for use of the aviator to drop free in respect to both frame sections when the same are separated, substantially as described.
4. In combination in an aeroplane a front frame section, a rear frame section, means for detachably connecting the two sections to descend independently, a seat for the aviator pivotally mounted on the rear frame section at the rear end of said seat, a support on the front frame section for the front end of said seat and a parachute for use of the aviator to descend independently of the two frame sections when separated, substantially as described.
5. In combination in an aeroplane, a front frame section, a rear frame section detachably connected with the front section, a weight arranged to be dislodged when the machine assumes an abnormal position and connections to the detachable connections between the frame sections to operate the same to release the rear section from the front section, when the weight is displaced, substantially as described.
6. In combination in an aeroplane, a front frame section, a rear frame section, wings mounted on the rear frame section, means detachably connecting the front and the rear frame sections and means for shifting the wings of the rear frame section automatically when the frame sections are detached from each other, said wings when shifted acting to retard the descent of the rear frame section and a parachute for the descent of the operator arranged to drop free of the two frame sections when detached, substantially as described.
7. In combination in an aeroplane front and rear frame sections, detachable connecting means between them at top and bottom thereof, a movable rod, means for operating said rod, a spring pressed member controlled for operation by the said rod and flexible connections extending from said spring pressed member to the detachable connections at the top and bottom of the aeroplane for detaching the rear frame section from the front frame section, substantially as described.
8. In combination in an aeroplane a front frame section, a rear frame section, detachable connections between them, a movable member with means between the same and the detachable connections for operating them, a hand lever for operating the said movable member and a weight arranged to be dislodged when the aeroplane assumes an abnormal position, the said movable member being operated as a result of the dislodgment of the weight, substantially as described.
9. In combination in an aeroplane a front frame section, a rear frame section, flexible or spring members extending from one section, bolts controlled by said flexible members to detach the rear frame section from the front frame section when the said flexible members are rendered free, means for holding the flexible members under stress when said means is in one position and connections for shifting said means to release the flexible members for detaching the frames from each other, substantially as described.
10. In combination in an aeroplane a front frame section, a rear frame section, means detachably connecting said sections, spring means for operating the detachable connections, sliding bolts for holding the spring means in a normal position and connections for operating the sliding bolts, whereby the spring means is allowed to exert its force to operate the detaching means, substantially as described.

In testimony whereof, I affix my signature.

HIPPOLYTE M. CHIRON.
